CLAIM

The ornamental design for a desk, as shown and described.

DESCRIPTION

FIG. 1 is a top right front perspective view of a desk showing my new design;

FIG. 2 is a bottom left rear view thereof;

FIG. 3 is a top plan view thereof;

FIG. 4 is a right side elevational view thereof;

FIG. 5 is a front elevational view thereof;

FIG. 6 is a rear elevational view thereof;

FIG. 7 is a bottom plan view thereof; and,

FIG. 8 is a right front perspective view thereof, showing a pedestal in broken lines to illustrate environment.

The portions of the desk shown in dotted lines do not form part of the claimed design.
